(57) **CLAIM**

The ornamental design for a spout, as shown and described.

DESCRIPTION

FIG. 1 is a perspective view of a spout showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is another perspective view thereof, with a shower sprayer engaged.

The dotted line showing of the shower sprayer is for illustrative purposes only and forms no part of the claimed design.
